ABSTRACT OF THE DISCLOSURE

Apparatus for feeding tobacco to a drier comprises a first conveyor which converts a continuous tobacco stream into a series of batches and dumps such batches into a vibrating trough wherein the batches are converted into an equalized mat. The leading end of the mat is fed into the drier.

The present invention relates to apparatus for treating tobacco leaf stock or other types of flowable solid materials. More particularly, the invention relates to improvements in apparatus which may be utilized for expelling surplus moisture from destalked or from destalked and shredded tobacco leaf laminae. Still more particularly, the invention relates to improvements in such parts or units of a tobacco drying or roasting apparatus which are utilized to feed tobacco into a drier wherein the tobacco particles are treated by contact with hot air or another suitable gaseous medium.

An apparatus which is utilized for drying or roasting of tobacco must meet two important requirements one of which includes proper temperature control of the heating medium and the other of which includes proper feed of tobacco into the drying or conditioning chamber. Our present invention is particularly concerned with improvements in such parts or units of a tobacco drying or roasting apparatus which are utilized to insure satisfactory admission of tobacco particles into a current of hot air or another gas. The importance of proper feed of tobacco into the drying or conditioning chamber of a drier will be readily understood by considering that even small variations in the rate of admission will result in excessive or insufficient expulsion of moisture so that the particles issuing from the conditioning chamber are too dry or contain excessive amounts of moisture. Even if the temperature of the hot gas is regulated in accordance with measurements which are carried out to determine the moisture content of successive increments of the tobacco stream prior and/or subsequent to drying, the inertia of various signal generating, transmitting and adjusting instrumentalities prevents timely adjustments in the temperature of hot gas. On the other hand, tobacco leaf stock which is stored for curing in the form of bales or in receptacles must have a moisture content which is within a very narrow range because, otherwise, the laminae will disintegrate if the moisture content is too low or will spoil in storage if the moisture content is too high. The manufacturers of cigarettes, cigars and similar tobacco-containing articles also insist that the moisture content of shredded tobacco should be within a narrow range such as is desirable to prevent excessive breakage of dry shreds or excessive adherence of moist shreds to each other.

Accordingly, it is an important object of the present invention to provide a tobacco drying or conditioning apparatus with novel and improved conveyor means which are constructed and arranged in such a way that they can feed to the conditioning chamber of a drier a succession

2

of increments each of which contains the same amount of tobacco.

Another object of the invention is to provide an apparatus for treatment of flowable material, particularly for drying of shredded or destalked tobacco leaf laminae, which can convert a continuous or discontinuous tobacco stream wherein successive increments might but need not contain the same amounts of material into a different stream (which may resemble a carpet or mat) and which is fully equalized before the leading end of such different stream reaches its destination, for example, the drying or conditioning chamber of a drier.

A further object of the invention is to provide an apparatus of the just outlined characteristics wherein the conversion of a stream of flowable material into an equalized mat can be readily observed at all times and wherein eventual inaccuracies may be eliminated without necessitating stoppage of the moving parts.

An additional object of the invention is to provide an apparatus which can be readily adjusted to deliver an equalized body of tobacco or other flowable solid material at a higher or lower rate.

A concomitant object of the invention is to provide an apparatus wherein the material to be treated is invariably sealed from the atmosphere, at least along the major part of its path through the apparatus, so that the expulsion of moisture or other treatment is localized in that area which is intended for such treatment.

Still another object of the invention is to provide a tobacco drying or conditioning apparatus which can utilize certain component parts of conventional conditioning apparatus, which occupies little room, which can treat tobacco at a desired rate, and which can be adjusted in more than one way to insure rapid elimination of inaccuracies in the feed of tobacco into the drier.

Briefly stated, one feature of our present invention resides in the provision of an apparatus for treating flowable material, particularly for expelling surplus moisture from particles of tobacco leaf stock. The apparatus comprises a feed for advancing a stream of flowable material lengthwise, first conveyor means including an inlet for receiving material from the feed, an outlet, and means (preferably including an air lock) for converting the material which is received through the inlet into successive batches containing equal amounts of material and for discharging such batches seriatim into the outlet by simultaneously sealing the inlet from the outlet against uncontrolled flow of air, and second conveyor means comprising a preferably trough-shaped conveying member having an intake end which is preferably sealingly coupled with the outlet of the first conveyor means and a discharge end which is distant from the intake end. The second conveyor means further comprises combined advancing and equalizing means for (a) advancing the batches in the conveying member from the intake end toward the discharge end so that such batches form a continuous carpet or mat of abutting batches extending from the intake end to the discharge end of the conveying member, and for (b) simultaneously equalizing the mat so that, at least when it reaches the discharge end of the conveying member, each successive increment of the mat has the same height and width and contains the same or substantially the same amount of material.

The discharge end of the conveying member may feed such successive increments into the lower portion of a preferably vertical duct which receives a current of hot air or another suitable gas through its lower end so that the ascending current of hot gas entrains the particles of material which is admitted through the discharge end of the conveying member and treats such particles while they advance with the current upwardly and through the duct.

The novel features which are considered as characteristic of the invention are set forth in particular in the appended claims. The improved apparatus itself, however, both as to its construction and its mode of operation, together with additional features and advantages thereof, will be best understood upon perusal of the following detailed description of a specific embodiment with reference to the accompanying drawings, in which:

FIG. 1 is a longitudinal central vertical section through an apparatus for treating tobacco;

FIG. 2 is a transverse vertical section as seen in the direction of arrows from the line II—II of FIG. 1; and

FIG. 3 is a fragmentary horizontal sectional view as seen in the direction of arrows from the line III—III of FIG. 2.

Referring to the drawings in detail, the apparatus of our invention serves to treat destalked shredded tobacco leaf stock. The treatment consists in that the apparatus expels from tobacco a certain amount of moisture so that the moisture content of material leaving the apparatus is within a predetermined optimum range such as is desirable when the tobacco is stored in bales or barrels for curing or when the tobacco is fed into a cigarette or cigar making machine.

The apparatus comprises a drier here shown as an upright duct 2 of rectangular (preferably square) cross-sectional outline. The lower end of the duct 2 is formed by an upwardly diverging cone 8 which is connected with a supply pipe 4 serving to admit a current of hot air or another suitable gaseous medium from a heater 4a. The upper end of the duct 2 is connected with a discharge pipe 6 which conveys the current of hot gas to a suction fan 6a.

The lower portion of the duct 2 is further connected with the discharge end 20 of a horizontal conveying member or trough 14 forming part of a conveyor B which discharges successive increments of an equalized tobacco carpet or mat M so that such increments are entrained by the current of hot gas and ascend therewith into the discharge pipe 6. The particles of tobacco are relieved of surplus moisture during travel through the duct 2 and are separated from the current of hot gas before the latter enters the inlet of the suction fan 6a. It will be seen that the discharge end 20 of the trough is located at a level above the cone 8 so that successive increments of the mat M enter a current of hot gas whose velocity has decreased in response to expansion during travel through the cone.

The trough 14 is of rectangular cross section and its width increases from the intake end 52 toward the discharge end 20. This is clearly shown in FIG. 3. The width of the discharge end 20 approximates the width of the side wall 10 of the duct 2. This discharge end 20 is received with clearance in an opening 12 provided in the side wall 10 and is sealingly coupled with this wall by an elastic sleeve 22 of rubber or synthetic plastic which is slipped onto the trough 14 and has a radially extending flange secured to the wall 10 by bolts, screws or similar fasteners 24.

The bottom wall of the trough 14 carries two pairs of lugs 15, 17 which are respectively connected with the upper ends of links 16, 18. The lower ends of the links 16, 18 are connected with stationary brackets 70, 71. Each link is pivotable about two horizontal axes so that the trough 14 can be vibrated by a device 25 including an electric motor 26 driving an endless belt 28 which drives the input shaft of a variable-speed transmission 30. The output shaft of the transmission 30 carries a wheel 33 provided with an eccentric pin for one end of a motion transmitting rod 32 the other end of which is articulately secured to a bracket 34 at the underside of the trough 14. When the motor 26 is started, the push rod 32 vibrates the trough 14 back and forth to thereby advance the mat M lengthwise toward the discharge end 20.

The side walls of the trough 14 are provided with transparent or translucent windows 36 which enable the operators to inspect the formation of the mat M and the progress of tobacco particles toward the discharge end 20.

The other conveyor A of the apparatus shown in FIGS. 1 and 2 receive a continuous tobacco stream T from a feed including an endless feed belt 58. The right-hand end turn of the belt 58 (as viewed in FIG. 2) discharges tobacco into a hopper 57 which constitutes the inlet of the conveyor A. The outlet 46 of the conveyor A resembles a vertical shaft of rectangular cross-sectional outline and is sealingly coupled to the intake end 52 of the trough 14 in a manner as shown in FIG. 1. The conveyor A further comprises a cylindrical housing 38 which extends between the inlet 57 and outlet 46 and accommodates an air lock (also called star feeder) 41. This air lock 41 comprises a horizontal shaft 40 which is parallel with the direction of movement of the mat M in the trough 14. The housing 38 is mounted on a stationary framework 42 which also supports a variable-speed electric motor 44 for the shaft 40. The air lock 41 further comprises a cylindrical sleeve 40a which is connected with the shaft 40 and carries four equidistant vanes or blades 64 located in planes including the axis of the shaft 40 and having axially parallel outer edges which travel along the internal surface of the housing 38 so as to prevent uncontrolled flow of air from the inlet 57 to the outlet 46. The air lock 41 is driven in a counterclockwise direction (see the arrow 72 in FIG. 2) and the vanes 64 define between themselves four cells 66.

The coupling between the outlet 46 of the conveyor A and the intake end 52 of the trough 14 comprises an elastic sleeve 48 which is slipped onto the intake end 52 and is fixed to the outlet 46 by bolts, screws or analogous fasteners 50. The sleeve 48 allows for vibration of the trough 14 but prevents uncontrolled flow of air into or from the interior of the outlet 46 and trough 14.

The belt 58 is driven by a second variable-speed electric motor 60 and its driven roller 58a is mounted in the side walls 54, 56 of the inlet 57.

The sleeves 22 and 48 insure that the interior of the trough 14 is completely sealed from the atmosphere. This will be readily understood since the air lock 41 of the conveyor A seals the inlet 57 from the outlet 46 and the discharge end 20 communicates solely with the conditioning chamber defined by the duct 2. Another important advantage of the sleeves 22 and 48 is that they cannot communicate vibrations of the trough 14 to the duct 2 and/or conveyor A.

The operation of our apparatus is as follows:

The motor 60 for the endless feed belt 58 is adjusted so that the belt advances the tobacco stream T lengthwise at a desired speed. The speed of the motor 44 for the air lock 41 is adjusted in dependency on the speed of the motor 60 (or vice versa) so that each successive cell 66 of the conveyor A receives a predetermined amount of tobacco whereby such tobacco forms a batch 74 which travels through the housing 38 (arrow 72) and descends by gravity through the outlet 46 and into the intake end 52 of the trough 14, i.e., onto the left-hand end portion of the trough, as viewed in FIG. 1.

The variable-speed transmission 30 of the vibrating device 25 is adjusted in such a way that the trough 14 removes a batch 74 from its intake end 52 before the conveyor A discharges the next batch 74a. Thus, successively delivered batches 74, 74a, 74b form the aforementioned carpet or mat M wherein the regions where the adjoining batches abut are characterized by relatively shallow transversely extending grooves or furrows 78. Since the width of the trough 14 increases toward the discharge end 20, and since the trough is continuously vibrated by the device 25, the depth of the grooves 78 decreases gradually and such grooves should normally disappear before the corresponding portion of the mat M reaches the discharge end 20. In other words, the vibrating

device 25 can be said to constitute a means for advancing the mat M lengthwise of the trough 14 and for simultaneously equalizing the mat so that each such increment of the mat which enters the lower portion of the duct 2 contains the same or substantially the same amount of tobacco. FIG. 1 shows clearly that the groove or furrow 78 between the rearmost batch 74b and the preceding batch 74a is substantially deeper than the groove or furrow 77 between the foremost batch 74 and the batch 74a. The variable speed drives (transmission 30 and motors 44, 60) for the conveyors B, A and the feed belt 58 are adjusted in such a way that the leading end of a freshly admitted batch 74b immediately abuts against the trailing end of the preceding batch 74a so that there are no voids between successive batches. The person looking through one of the windows 36 can readily observe the equalizing operation and, if such equalizing operation is not entirely satisfactory, adjustment of the transmission 30, motor 44 and/or motor 60 can rapidly eliminate any inaccuracies so that each successive increment of the mat M will invariably contain the same amount of tobacco before such increments reach the discharge end 20. The fact that the trough 14 diverges toward its discharge end 20 also contributes to highly satisfactory equalizing action. Furthermore, and since the trough 14 vibrates at all times, any agglomerations of tobacco particles which are still present in the intake end 52 will disappear on their way toward the discharge end 20 so that the duct 2 receives loose tobacco particles each of which is fully exposed to the moisture-expelling action of the current of hot gas admitted by the supply pipe 4. As stated before, particles of tobacco traveling upwardly through the duct 2 and into the discharge pipe 6 will be separated from the current of hot gas before the latter enters the inlet of the suction fan 6a. Such separation of treated tobacco can be carried out in a very simple way by reducing the speed of the current of hot gas so that the solid fraction can descend by gravity. The discharge end 20 of the trough 14 discharges tobacco into the lower portion of the duct 2 so that such tobacco is brought into contact with air which is still hot and is capable of expelling requisite amounts of moisture. Also, such admission of tobacco into the lower portion of the duct 2 enables the current of hot air to disperse the particles across the full width of the duct so that each such particle is fully exposed.

The windows 36 also enable the persons in charge to reduce the speed of the transmission 30 or to increase the speed of the feed belt 58 if the successively delivered batches 74, 74a, 74b do not touch each other. The persons in charge will reduce the speed of the motors 44 and 60 if the successively delivered batches overlie each other, i.e., if the particles discharged by a first cell 66 are not fully removed from the intake end 52 prior to admission of particles from the next-following cell 66.

The adjustability of the drives for the feed belt 58 and conveyors A and B further enables the personnel to regulate the drying action in a very simple and accurate way. The amounts of tobacco admitted to the duct 2 per unit of time will determine the extent to which the current of hot air is cooled on contact with tobacco. On the other hand, the moisture-expelling action of the current of hot gas is dependent on its temperature. Thus, by regulating the speed of the mat M along the trough 14, and by regulating the amounts of tobacco contained in successive increments of the mat, the operators can regulate the drying action in the duct 2. The amounts of tobacco in successive increments or unit lengths of the mat M can be regulated by proper adjustment of the motor 60 for the feed belt 58.

An important advantage of an air lock whose shaft 40 rotates about a horizontal axis which is parallel to the direction of movement of the mat M is seen to reside in that such an air lock can form and discharge batches (74, 74a, 74b) which contain identical or nearly identical amounts of tobacco and that each batch has the same

shape as the preceding batch. Therefore, the batches 74, 74a, 74b can be readily converted into a continuous mat which is then fully equalized during travel in the trough 14. It will be seen that the leading end of the mat M which is admitted into the lower portion of the duct 2 has a relatively small height. This is of advantage because experiments carried out with our apparatus indicate that a relatively wide mat of small height can be fed more uniformly than a higher mat and that successive increments of a wide but flat mat can be more readily entrained and dispersed by the current of hot gas flowing upwardly in the duct 2.

Without further analysis, the foregoing will so fully reveal the gist of the present invention that others can, by applying current knowledge, readily adapt it for various applications without omitting features which fairly constitute essential characteristics of the generic and specific aspects of our contribution to the art and, therefore, such adaptations should and are intended to be comprehended within the meaning and range of equivalence of the following claims.

What is claimed as new and desired to be protected by Letters Patent is:

1. Apparatus for treating flowable material, particularly for treating tobacco, comprising a feed for advancing a stream of material lengthwise; first conveyor means comprising an inlet for receiving material from said feed, an outlet, and means for converting the material which is received through said inlet into successive batches and for discharging such batches into said outlet by simultaneously sealing said inlet from said outlet; and second conveyor means comprising a conveying member having an intake end connected with said outlet and arranged to receive successive batches from said first conveyor means and a discharge end distant from said intake end, said second conveyor means further comprising means for advancing said batches in said conveying member from said intake end toward said discharge end so that such batches form a continuous mat which extends from said intake end to said discharge end and wherein successive batches comprise portions of increasing height, and for simultaneously equalizing said mat so that, on reaching said discharge end, each successive increment of the mat contains substantially the same amount of material.

2. Apparatus as set forth in claim 1, wherein the means for converting material into batches comprises an air lock having a member rotatable about an axis which is parallel with the direction in which the mat advances in said conveying member.

3. Apparatus as set forth in claim 1, wherein said conveying member is an elongated trough and wherein said mat advancing and equalizing means comprises a device for vibrating said trough.

4. Apparatus as set forth in claim 1, further comprising coupling means providing a fluidtight connection between said outlet and said intake end.

5. Apparatus as set forth in claim 1, further comprising independent variable-speed drive means for each of said conveyor means.

6. Apparatus as set forth in claim 1, further comprising independent variable-speed drive means for at least one of said conveyor means and for said feed.

7. Apparatus as set forth in claim 1, wherein said conveying member is provided with at least one transparent portion to permit visual observation of the formation and equalization of said mat.

8. Apparatus for treating tobacco, comprising a feed for advancing a stream of tobacco lengthwise; first conveyor means comprising an inlet for receiving tobacco from said feed, an outlet, and means for converting tobacco which is received through said inlet into successive batches and for discharging such batches into said outlet by simultaneously sealing said inlet from said outlet; second conveyor means comprising an elongated

trough having an intake end connected with said outlet and arranged to receive successive batches from said first conveyor means and a discharge end distant from said intake end, said second conveyor means further comprising a device for vibrating said trough to thereby advance said batches in the trough from said intake end toward said discharge end so that such batches form a continuous mat extending from said intake end to said discharge end, and to simultaneously equalize said mat so that, on reaching said discharge end, each successive increment of the mat contains substantially the same amount of tobacco; and a drier arranged to receive tobacco from the discharge end of said trough, said drier comprising an upright duct having a lower portion sealingly connected with said discharge end to receive successive increments of the equalized mat, and means for admitting a current of hot gas into said duct below said lower portion thereof so that the current rises in and entrains the particles of tobacco through said duct.

9. Apparatus for treating flowable material, particularly for treating tobacco, comprising a feed for advancing a stream of material lengthwise; first conveyor means comprising an inlet for receiving material from said feed, an outlet, and means for converting the material which is received through said inlet into successive batches and for discharging such batches into said outlet by simultaneously sealing said inlet from said outlet; and second conveyor means comprising an elongated trough located in a substantially horizontal plane and having an intake end connected with said outlet and arranged to receive successive batches from said first conveyor means and discharge end distant from said intake end, said second conveyor means further comprising a device for vibrating said trough to thereby advance said batches in said trough from said intake end toward said discharge end so that such batches form a continuous mat extending from said intake end to said discharge end, and to simultaneously equalize said mat so that, on reaching said discharge end,

each successive increment of the mat contains substantially the same amount of material.

10. Apparatus for treating flowable material, particularly for treating tobacco, comprising a feed for advancing a stream of material lengthwise; first conveyor means comprising an inlet for receiving material from said feed, an outlet, and means for converting the material which is received through said inlet into successive batches and for discharging such batches into said outlet by simultaneously sealing said inlet from said outlet; and second conveyor means comprising an elongated trough having an intake end connected with said outlet and arranged to receive successive batches from said first conveyor means and a discharge end distant from said intake end, the width of said trough increasing in a direction from the intake end toward the discharge end thereof and said second conveyor means further comprising a device for vibrating said trough to thereby advance said batches in said trough from said intake end toward said discharge end so that such batches form a continuous mat extending from said intake end to said discharge end, and to simultaneously equalize said mat so that, on reaching said discharge end, each successive increment of the mat contains substantially the same amount of material.
